(57) **CLAIM**

The ornamental design for a ‘connector for child balancing play game assembly’, as shown and described.

DESCRIPTION

FIG. 1 is a perspective view of my new design;

FIG. 2 is a front, rear, left side, or right side elevation view thereof;

FIG. 3 is a top plan view thereof;

FIG. 4 is a bottom plan view thereof; and,

FIG. 5 is a reduced scale perspective view showing the design in use, the broken line showing the environmental structure being for illustrative purposes only and forming no part of the claimed design.
